UNITED STATES PATENT OFFICE.

ELBERT G. CHANDLER, OF PORTLAND, OREGON.

CAR-TRUCK.

1,222,931.

Specification of Letters Patent. Patented Apr. 17, 1917.

Application filed August 12, 1915. Serial No. 45,085.

To all whom it may concern:

Be it known that I, ELBERT G. CHANDLER, a citizen of the United States, residing in the city of Portland, county of Multnomah, 5 and State of Oregon, have invented certain new and useful Improvements in Car-Trucks, of which the following is a specification.

My invention relates to car trucks, and 10 more particularly to certain improvements therein intended to cheapen and at the same time improve and strengthen the construction thereof, and to make possible the use of certain cast steel parts in connection with 15 flat steel, instead of all flat steel, as now used.

In order that others may understand my improvement, I have shown its practical embodiment in a car truck, which I will now 20 describe in detail.

Figure 1 is a side elevation of a car truck embodying my invention;

Fig. 2 is an enlarged side elevation of the portion of the truck embodying my invention; 25

Fig. 3 is a top plan view thereof;

Fig. 4 is a side elevation of a modification of the invention; and

Fig. 5 is a top plan view thereof.

Referring now more in detail to the drawings, the invention consists in providing a combination heel-brace and journal-box column. My combination device in the drawings is designated as a whole, 6, and comprises the guide portion, or journal-box column, 6^a, the top portion 6^b, the brace portion 6^c, with the strengthening web 6^d, all cast in one piece, as clearly indicated in Figs. 2 and 3. The journal-box column 6^a, 30

is provided with a bolt hole 6^e extending longitudinally therethrough, and is adapted to receive a bolt 7, for clamping the top plate, or bar, 8, upon said heel-brace 6, and also the lower plate, or tie-bar, 9, as clearly indicated in Fig. 1. It is frequently the case that where the lower strip, or tie-bar, 9, for example, is continued upwardly to the strip, or bar, 8, in the position occupied by the brace-portion 6^c, of my combination device, and bolted at its upper end to the outer end of the upper bar 8, that said bars are bent downwardly at their outer ends under unusual load, or by some unusual blow, so that the top of the truck is no longer 50 straight but the outer ends are turned downwardly and can not be straightened without

the necessity of removing them which requires a great deal of work. By providing a one piece cast combination heel-brace and guide, the supporting strength of the outer 6^a ends of the top bar 8, is materially increased, and the construction is simplified and cheapened by casting the guide part and the brace as one piece.

In Figs. 4 and 5, I have shown a similar 65 construction in which I have carried the idea a little further, and have included both journal-box columns, with a connecting portion, designated 10, forming a seat for the upper end of the spring 11. In this construction, as shown in Figs. 4 and 5, the guide columns, designated 6^a and 12, are both provided with bolt holes 13—13, extending lengthwise thereof by means of which the top bar 8, and the bottom bar 9, 75 and also the ends of a truss bar 14, are firmly and effectively bolted together with the journal-box, yieldingly seated between the journal-box columns 6^a and 12. Thus I have provided a very simple and very practical construction in which a cast or one piece-heel-brace can be combined with the usual flat, or arch, bars, the same being bolted together in a way to give a very simple, 80 practical and economical structure possessing great strength, and also a structure in which any of the parts can be quickly and readily removed and replaced by similar new parts.

I do not limit the invention to the specific 90 form here shown, except as I may be limited by the hereto appended claims forming a part hereof.

I claim:

1. A combination integral heel-brace and 95 journal-box column for car trucks, comprising a journal-box column with a bolt hole extending longitudinally therethrough, a horizontal top portion, a brace portion connecting the outer end of said top portion 100 with the lower end of said journal box column, all cast in one piece, said combination heel-brace and journal-box being adapted to be secured in place in said car truck by means of a bolt extended longitudinally 105 through said bolt hole in the journal-box column, substantially as described.

2. In combination with the top and lower bars and journal-box of a car truck, a combination integral heel-brace and journal-box 110 column, cast in one piece, and comprising a journal-box column portion having a bolt

hole formed therein longitudinally thereof, and a triangular frame-like portion formed at one side thereof, said combination heel-brace and journal-box column being secured 5 between said top and lower bars by means of a bolt extended through said top bar, said journal-box column and said lower bar, substantially as shown and described.

3. A combination heel-brace and journal-10 box columns cast in one piece and comprising journal-box column portions having bolt holes formed therein longitudinally thereof,

a connecting portion between the upper ends thereof forming a seat and a bracket-like portion, all substantially as shown and de- 15 scribed.

In witness whereof I have hereunto set my hand at Portland, Multnomah county, Oregon, this 6th day of August, 1915.

ELBERT G. CHANDLER.
